UNITED STATES PATENT OFFICE

2,364,859

LOOSE-LEAF BINDER

Leo Lichtenstein, Chicago, Ill.

Application July 1, 1943, Serial No. 493,045

1 Claim. (Cl. 129—1)

This invention relates to a construction of loose leaf binder and more particularly to a novel and improved construction of the loose leaf binder ring.

Binder rings embodying the invention are adapted for use with loose leaf binders and loose leaf ledgers, memorandum books and the like. Heretofore, insofar as I am aware, loose leaf binder rings customarily have been made entirely of metal, supplies of which often, and more particularly at the present time, are limited.

An object of my invention is to provide a loose leaf binder ring of strong yet simple construction, which is made entirely of plastic material, thereby eliminating entirely the use of metal in such construction.

Another object of the invention is to provide a loose leaf binder ring of the character described having novel and improved means associated therewith and formed integrally therewith for securely attaching the same to the back member of the loose leaf binder.

Another object of my invention is to provide a novel and improved loose leaf binder ring entirely made of a non-metallic material comprising a base portion which may be disposed in substantially flat relationship on the back member of the binder and secured thereto in such position by a rivet or the like extending through said base portion whereby the ring will be held in a substantially rigid position with respect to the back member.

A still further object of the invention is to provide a loose leaf binder ring of the character described constructed entirely of non-metallic material and comprising a base portion having a pair of substantially semi-circular arms extending from said base portion with the free ends of said arms overlapping and being normally disposed in transversely spaced relation, said free ends being provided with means for automatically interlocking when such ends are abutted endwise whereby all parts of the ring will be in continuous and unbroken arcuate disposition.

A still further object of my invention is to provide a loose leaf binder ring of the character described which may be constructed of non-metallic material, which may be produced along lines convenient for low cost manufacture and which at the same time will be highly efficient for carrying out the purposes for which it is designed.

With the foregoing and other objects in view which will appear as the description proceeds, the invention consists in certain novel features

of construction, arrangement and combination of parts, hereinafter fully described, illustrated in the accompanying drawing, and particularly pointed out in the appended claim, it being understood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof, from an inspection of which, when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a view in perspective of a loose leaf binder ring embodying my invention.

Fig. 2 is a top plan view of the same in closed position with parts thereof being shown in section to more clearly illustrate the same.

Fig. 3 is a view similar to Fig. 2 with the ring being shown in open position.

Fig. 4 is a side elevational view of the ring, the same being shown in open position.

Fig. 5 is an end elevational view of the ring shown in Fig. 4.

Fig. 6 is a sectional view through a loose leaf binder showing one of the rings embodying my invention secured thereto with parts thereof being shown in section.

Stated generally, the invention contemplates the construction of a loose leaf binder ring made entirely of non-metallic material, such as a phenol plastic material or the like in place of the metal ring heretofore customarily used for this purpose.

The ring proper comprises a substantially annular base portion, the lower face of which is relatively flat and may be suitably serrated or knurled, which serrated portion may be placed in contacting engagement with the back member of the looseleaf binder when the ring is secured in place to the binder. Extending from said base portion are a pair of arcuate arms of substantially semi-circular formation, the free ends of said arms being offset in transversely spaced overlapped relation, in which position they will be normally retained by the inherent resiliency of the material. When in this posi-

tion, the free ends of the arms will be transversely spaced from each other and will thus permit the threading of the paper sheets thereon. When it is desired to close the ring, the ring may be slightly expanded and the ends thereof abutted endwise, in which position the ring will be automatically locked and the same will be in a continuous and unbroken arcuate disposition.

Referring specifically to the drawing by characters of reference, the particular form of binder disclosed consists of a back member 10 and a pair of cover members 11 on opposite sides of the back member. As shown in Fig. 6, my improved binder ring is adapted for rigid attachment with the back member 10, in which position the ring will rest solidly and against any wobbling or other movement on the back member. The ring proper consists of a base portion 12 which may be of substantially annular formation and a size sufficient to give a firm support to the ring when secured to the back member 10. The lower surface of the annular base portion 12 is knurled or serrated, as shown at 13, for the purpose of biting into the back member 10 when the two are in assembled position with each other. A suitable opening 14 is provided through the portion 12 which opening is counter-sunk, as shown at 15, and through which opening is adapted to extend a suitable rivet 16 having a head 17 by means of which the said ring is permanently and rigidly secured to the back member 10.

Formed integral with the base portion 12 are a pair of substantially semi-circular arms 18 and 19, said arms extending from substantially diametrically opposed points of said base portion and are arranged so that the free ends thereof, as shown more clearly in Fig. 3, will be in overlapping relation and normally spaced apart transversely of the ring. The inherent resiliency of the material from which the ring is constructed will normally hold the ends thereof in such transversely spaced position.

As already stated, the ring may be cast from suitable phenol plastic material, which material has been found will have the necessary inherent resiliency for accomplishing the purposes hereinabove set forth. The arm 19 is provided at its free end with the conical extremity 20 and the arm 18 has formed in its extremity a conical socket 21 within which said portion 20 is adapted to be received.

When it is desired to close the ring, the same may be slightly expanded and the free ends of

the arms 18 and 19 moved to a position where they will be disposed in the same vertical plane whereby the ends of the ring may then be caused to move into interlocking engagement in which position the said ends will abut closely in arcuate disposition in the same plane. The ring will be securely closed and held in such closed position by the interlocking of the portions 20 and 21.

10 Due to the rigid support afforded the ring member by reason of the base portion being in engagement with the back member 10, it will be apparent that the ring may be opened and closed a great number of times without loosening the same from its support with the back member. It will also be apparent that the construction and design of the ring readily lends itself to manufacture from non-metallic materials, as well as being economical in both construction and assembly with the loose leaf binder.

15 It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claim.

20 What I claim and desire to secure by Letters Patent of the United States is:

25 A binder ring made of non-metallic, resilient material comprising a circular base portion, a pair of arcuate arms extending upwardly from said base portion and joined at diametrically opposite points to the peripheral edge of said base portion, said arms having their free ends normally in overlapped transversely spaced relation, a socket on the free end of one of said arms, said socket being adapted to receive the end of the other arm when the free ends of the arms are spread apart and urged into alignment laterally so that the inherent resiliency of the arms tends to hold the free ends in tight abutment, and serrations on the bottom face of said base, said base having an axial opening for receiving a rivet therethrough by means of which the binder ring is fastened to a binder in such manner that the serrations will engage in the binder to prevent rotation of the binder ring.

40 LEO LICHTENSTEIN.
